R. W. BARTON

CIRCULATING AND AGITATING DEVICE

Filed Feb. 14, 1923

Patented May 19, 1925.

1,538,508

UNITED STATES PATENT OFFICE.

RENSSELAER W. BARTON, OF BINGHAMTON, NEW YORK.

CIRCULATING AND AGITATING DEVICE.

Application filed February 14, 1923. Serial No. 619,039.

To all whom it may concern:

Be it known that I, RENSSELAER W. BARTON, a citizen of the United States, residing at Binghamton, in the county of Broome and State of New York, have invented certain new and useful Improvements in Circulating and Agitating Devices, of which the following is a specification.

My invention relates to improvements in circulating and agitating devices, for use in tanning, dyeing and other purposes and it has for its object to provide an agitator which automatically compensates for the fluid being circulated. I accomplish these results by a series of sliding valves, operated by floats, the valves being mounted on a tube, thru which the fluid is forced by centrifugal pumps and the opening and closing of the valves is controlled by the depth of the fluid in the vat or other receptacle containing the fluid. In case the tank is full, all the floats will rise and the valves close and the fluid flows out of the upper end of the pipe, and as the level of the liquid drops to a point such that the upper float is no longer raised by the level of the liquid; the float will drop, thus opening the corresponding upper valve, relieving the flow of the liquid to a new lower level. As the level continues to fall, corresponding floats will drop, opening the valve and flow of the liquid at a new level. This action insures the maximum vertical lift and consequent maximum agitation of the liquid.

With these objects in view, my invention consists in certain novel features of construction and arrangements of parts, as will be hereinafter more clearly described and pointed out in the claims, reference being had to the accompanying drawings, in which:

Fig. 1 is a side view of my device.

Fig. 2 is a side view of a fragmentary part of my device partly in cross section.

Fig. 3 is a plan view of a part of my device.

Fig. 4 is a plan view of a part of my device.

Fig. 5 is a plan view of a part of my device.

Fig. 6 is a side view of a part of my device.

The same reference characters denote like parts in each of the several figures of the drawings.

In carrying out my invention, in a suit-

able vat or container B I provide a sectional tubular vertical body portion A, which may be rectangular in form, as shown in the views or circular and composed of a series of sections or casings 2. 2. 2, spaced apart by the open spaces 3. 3. 3 and each supported on the interior vertical supports 5. 5. 5, mounted in the interior corner of the sections 2. 2. 2, which supports 5. 5. 5, are 60 mounted upon the base 6, which is composed of the top 6', the end wall 7 and the base 8. Mounted in any convenient manner within the casing structure A, I have the vertical pulley and power 65 shaft 9, having its lower end mounted in the impeller or propeller 10 of a centrifugal pump, which is pivotally mounted on the base plate 11 and on the top of shaft 9. I have the pulley 12 or other propelling device 70 and also rigidly mounted on the shaft 9, below pulley 12, and above casing A, I have the disk X supported in any convenient manner. The impeller 10 as is shown in Fig. 1 opens into the channel Y, formed by 75 the end wall 7 and base partition 8, which forms a passage channel 13, up into the vertical sectional body portion A. Mounted on the outside of the sections 2. 2. 2, I have the parallel lugs or support 14. 14. 14; slidably mounted on the exterior of the sections 2. 2. 2, I have the sleeves 15. 15. 15, each having on the two opposite sides thereof, the vertical lugs 16. 16. 16 and pivotally mounted in the side supports 14. 14. 14, I have the 80 forked lever 17. 17. 17, the parallel ends of which have pivotal connection with the vertical lugs 16. 16. 16; each forked lever 17 has centrally mounted in its outer surface, the rod 18, on the end of which is 85 mounted a hollow float 19. Mounted on the pulley 12 I have a belt or other means connecting with any convenient source of power 90 for the operation of the pump.

In the operation of my device, having applied the power to the pulley 12 and produced the operation of the pump thru the shaft A, the revolving of the centrifugal pump draws the liquid from the bottom of the vat or tub, forcing it up thru the channel 13; and the lowering of the liquid causes the float 19 to fall, thereby acting upon the lever 17 causes it to raise the sleeve 15 and open the sectional space 3 between the sections and causes the liquid to pass out at that point from the tubular casing and so on with the several sliding sleeves along the casing A by 100 105 110

the operation of the floats effected by the liquid, and causing the sleeves or gates to rise or fall and to open and close the section openings 3. 3. 3, thereby creating an even and continuous circulation thru the entire liquid area as before described. As the liquid rises, the float carried by its surface is lifted and operating the lever 17, moves the sleeve 15 downward, closing the corresponding opening 3, thus forcing the liquid to a higher level, until the next upper section at opening 3 is reached when it flows out thru the opening 3, causing the surface level to rise and with it, the float which closes the corresponding opening 3, as before described. When the liquid reaches the top of casing A, it flows out of the casing and contacts with revolving disk X which causes the liquid to spray and be further agitated.

Having thus described my invention what I claim as new and for which I desire Letters Patent, is as follows:

1. In an improvement in circulating and agitating devices, a vat, containing the liquid to be agitated; a vertical sectional tubular housing, mounted in a base chamber support on the floor of the vat; a channel opening therethru to said housing; a pivoted centrifugal pump impeller mounted in said base chamber, adjacent to the channel opening; a shaft mounted in said impeller and extending upward thru the housing; a pulley, mounted thereon and connecting means between said pulley and a source of power, openings thru the housing sections, sliding sleeves, mounted on the housing, adapted to removably close the openings; lugs mounted on the housing, supporting a forked lever having pivotal connection with the sleeves, a float mounted on the outer end of lever, adapted to be raised or lowered with the rise or fall of liquid within the receiving vat.
2. In an improvement in circulating and agitating devices; a vat, containing the liquid to be agitated, a vertical sectional tubular housing with sectional openings in the same, mounted in the vat; a channel opening into the base of said housing; a centrifugal pump impeller mounted ad-

jacent to said channel; means for propelling said pump, connected with a source of power; sliding sleeves mounted on the housing, each sleeve having pivotal connection with a lever, mounted on the housing and sustaining a float, mounted thereon, adapted to be raised or lowered with the rise or fall of the liquid within the receiving vat, caused by the movement of the pump.

3. A circulating and agitating device comprising a pump having an outlet, an upstanding conduit communicating with the pump outlet, said conduit being provided intermediate its ends with a plurality of discharge openings and float controlled devices for opening and closing said openings adjacent the surface level of the liquid.

4. A fluid circulating and agitating device comprising a vat containing the fluid to be circulated and agitated, a pump within the vat, an upstanding discharge conduit from the pump, said conduit provided at different levels with outlet openings, float operated valves for controlling the outlet openings and a deflector at the upper end of the discharge conduit.

5. In a circulating and agitating device, a vat, a circulating pump for withdrawing fluid from near the bottom of the tank and discharging it above the pump and means for maintaining the discharge from the pump adjacent the surface of the liquid at different levels.

6. A process of circulating and agitating liquids comprising withdrawing the liquid from the bottom of a container and automatically discharging it adjacent the surface level of the liquid in the container regardless of the level of the liquid.

7. A method of circulating and agitating comprising withdrawing the liquid from near the bottom of a container, discharging it adjacent the surface level thereof, and automatically compensating for the variations in the height of the level of the liquid circulated.

In testimony whereof I have affixed my signature.

RENSSELAER W. BARTON.
